SHOE SOLE

Axel D. Duckert, Copenhagen, Denmark, assignor to
Dansk Gummi Industri v/Axel Duckert, Soborg,
Denmark

Filed Nov. 12, 1964, Ser. No. 82,575

Claims priority, application Denmark May 28, 1964

Term of patent 14 years

(Cl. D7—5)

FIG. 1 is a bottom perspective view of a shoe sole showing my new design, the design indicated on the ball portion being continuous from the ridge toe portion to the heel portion; and

FIG. 2 is a sectional view taken on the line 2—2 of FIG. 1.

I claim:

The ornamental design for a shoe sole, as shown and described.
